FIG. 2 is a front elevational view thereof with the scarf shown
lying flat;

FIG. 3 is a rear elevational view thereof with the scarf shown
lying flat;

FIG. 4 is a left side elevational view thereof, the right side elevational view being a mirror image thereof;

FIG. 5 is a top plan view thereof; and,

FIG. 6 is a bottom plan view thereof.

The broken lines showing a person in FIG. 1 are included for the purpose of illustrating the invention in use, and form no part of the claimed design. The broken line trim in FIG. 3 is a portion of the decorative scarf that forms no part of the claimed design. The remaining broken lines represent stitching.
